ROTARY STEAM OR FLUID MOTOR

Samuel C. Carter and Frank H. Metke,
Glendale, Calif.

Application August 28, 1933, Serial No. 687,135

8 Claims. (Cl. 121—71)

This invention relates to a steam or fluid driven engine or motor, and it is a general object of the invention to provide a simple, practical and efficient motor of this character.

Another object of the invention is to provide an improved fluid motor or engine that initially directly develops rotary power and therefore produces little or no vibration.

Another object of the invention is to provide an improved motor capable of being operated or driven by steam or other suitable vapor or fluid under pressure.

Another object of the invention is to provide an engine or fluid motor that does not include any large or heavy reciprocated parts. The elements of the motor provided by the invention that are acted upon or that receive the driving force of the actuating steam or fluid pressure are rotatable and have direct operative connections with the shaft of the engine.

Another object of the invention is to provide a steam or fluid motor that includes two rotatable members or motors that are driven or acted upon by the actuating fluid under pressure for the major portions of their strokes or revolutions.

It is another object of the invention to provide a steam or fluid motor of the character mentioned that is easy to regulate and control and that may readily reverse to drive the engine shaft in the counter-clockwise direction as well as in the forward or clock-wise direction.

It is another object of the invention to provide a steam or fluid motor that develops substantially constant or unvarying continuous power and therefore may not require a fly wheel.

Another object of the invention is to provide a steam or fluid motor of the character mentioned that is compact and entirely self-contained.

Other objects and features of the invention will be better and fully understood from the following detailed description of a typical form and application of the invention, throughout which description reference is had to the accompanying drawings, in which:

Fig. 1 is a side elevation of the motor provided by the present invention showing a portion of the valve gear housing broken away to illustrate the principal parts of the valve gear in elevation. Fig. 2 is a longitudinal vertical detailed sectional view taken substantially as indicated by line 2—2 on Fig. 3. Fig. 3 is a transverse vertical detailed sectional view taken as indicated by line 3—3 on Fig. 2. Fig. 4 is a detailed sectional view of the timing gears, being a view

taken substantially as indicated by line 4—4 on Fig. 3, and Fig. 5 is an enlarged transverse detailed sectional view taken substantially as indicated by line 5—5 on Fig. 2.

The present invention is capable of embodiment in forms for various purposes and for various installations, and is capable of efficient operation when driven by practically any class of fluid under pressure, however it is particularly adapted for operation by steam or other vapors. In the following detailed description, we will disclose a typical form of the invention, it being understood that the invention is not to be considered as limited or restricted to the specific construction about to be described or to the operation of the motor by any specific kind or class of fluid.

The engine or fluid motor provided by the present invention includes generally, a body or block 10 having two bores or chambers, 11, rotatably driving members or driving rotors 12 in the chambers 11, a master rotor 13 at the axis of the engine engaging the driving rotors 12, reversing valves 14, control valves 15, and a valve gear 16 for operating the control valves 15.

The body or block 10 of the motor may be varied considerably in shape, construction, etc., depending on the size, use or installation of the motor. In the particular embodiment illustrated, the block 10 is an elongate horizontally disposed member of rectangular cross section. The block 10 may be supported on suitable legs or mounting brackets 17, it being understood that the block 10 may be arranged in any position and mounted in any suitable or practical manner. The chambers 11 in which the driving rotors 12 operate extend

horizontally and transversely through the block 10 from one side to the other. The chambers 11 are preferably of the same diameter and length, and are round in cross section and uniform in diameter throughout their lengths. In accordance with the invention, the chambers 11 are spaced apart, being located adjacent to the ends of the block 10. A central chamber or bore 18 extends transversely through the block 10 from one side to the other to carry the master rotor 13.

The central bore 18 is preferably smaller in diameter than the chambers 11 and its opposite sides join or communicate with the chambers 11. Side plates 19 are suitably bolted to the opposite sides of the block 10 and extend over the ends of the chambers 11 and bore 18. The side plates 19 are provided with openings 20 concentric with the chambers and bore for carrying

bearing housings 37.

The driving members or driving rotors 12 are

110

105

rotatable in the chambers 11 and are adapted to be acted upon or directly rotated by the actuating fluid pressure. The rotors 12 are cylindrical in configuration and are considerably smaller in 5 diameter than the bores or chambers 11 so that they are surrounded by annular fluid receiving spaces. The peripheries of the rotors 12 are accurately and smoothly finished to cooperate with the master rotor 13 as will be subsequently de- 10 scribed. Peripheral grooves 21 are provided in the opposite ends of the rotors 12 for carrying wear rings 22 of cast iron or the like. The rings 22 are pressed in the grooves 21 and are adapted to bear against or have engagement with the inner sides of the hardened side plates 19. The 15 driving rotors 12 are carried by the shafts 23 and are keyed thereto at 12^a. Recesses 24 are provided in the opposite ends of the rotors 12 around the shafts 23 to receive the inner portions of bearing housings 25. The bearing housings 25 carry packing means or glands 26 for sealing about the shafts 23. The glands 26 prevent any condensation from reaching the bearing and prevent steam leaks around the shaft. The shafts 23 are shouldered at 23^a and anti-friction bearings 27 are provided around the shouldered portions of the shafts to support the shafts in the mountings 25. Bearing retainers or caps 28 are attached to and close the outer sides of the bearing housings 25. 20 The shafts 23 of the driving rotors 12 extend through openings in the caps 28 and are packed about by packing 29.

In accordance with the invention, each of the 30 driving rotors 12 is provided with a tooth or vane 30. The vanes 30 extend axially of the rotors 12 and project from their peripheries to operate in the annular or open portions of the chambers 11. Dove tailed or undercut axial grooves 31 are provided in the peripheries of the driving rotors 12 35 and extend through the wear rings 22. The base portions of the vanes 30 have inwardly divergent sides 30^a to fit in or cooperate with the grooves 31 to lock the vanes in position. The driving vanes 30 are adapted to be acted upon by 40 or receive the driving energy of the actuating steam or fluid under pressure and extend between the opposite ends of the chambers 11. In the preferred construction, the vanes 30 have cross sectional configurations similar to involute spur 45 gear teeth, having curved or convexed side faces 50 32. The tops or outer ends 33 of the vanes 30 may clear the walls of the chambers 11 with but very slight clearance so that they do not actually contact with the chamber walls and are not subjected to wear, however it may be preferred to 55 have outer ends 33 of the driving vanes in effective sliding engagement with the walls of the chambers as illustrated in the drawings. The driving teeth or driving vanes 30 are preferably 60 hardened.

The master rotor 13 rotates in the central bore 18 and cooperates with the two driving rotors 12. The master rotor 13 is a cylindrical member whose periphery closely or accurately fits the bore 18 65 without actually engaging the walls of the bore. The master rotor 13 has rolling engagement with the peripheries of the driving rotors 12. Peripheral grooves 34 are provided in the opposite ends of the master rotor 13 to carry wear rings 35 which bear against or engage the end plates. The central or master rotor 13 extends from one end to the other of the bore 18 to completely occupy or 70 fill the bore. The engagement of the master rotor 13 with the driving rotors 12 and the co-operation of the vanes 30 with the walls of the 75

chambers 11 divides each of the annular spaces in the chambers into two distinct portions, namely, a high pressure portion at the rear of the vane relative to its direction of rotation, and a low pressure or exhaust portion in front of the vane. 80 A longitudinal or axial groove 34^a is provided in the periphery of the master rotor 13 and extends through the wear rings 35 to the end walls of the bore 18. The movement of the rotors 12 and 13 is related or synchronized so that the groove 34^a 85 successively or alternately receives the vanes 30. The groove 34^a is shaped to effectively receive the driving vanes 30 without contacting with the surfaces of the vanes.

The master rotor 13 is carried by a central shaft 90 35 and is provided at its opposite end with central recesses 36. The rotor 13 is keyed to the shaft at 35^b. Bearing housings 37 are attached to the side plates 19 and have reduced inner portions extending into the recesses 36. Packing glands 38 are carried by the bearing housings 37 to seal about the shaft 35^a. Suitable ball bearings 39 are provided in the housings 37 to carry the shaft 35^a 95 for free rotation. Bearing retaining plates or caps 40 close the outer ends of the bearing housings 37. The shaft 35^a of the master rotor 13 extends through an opening in one of the caps 40 to project from a side of the engine to form the engine shaft.

An operative connection is provided between the shafts 23 and the shaft 35^a to synchronize the movement of the driving rotors 12 with the movement of the master rotor 13 and to form an operative drive between the driving rotors of the engine shaft 35^a. This timing and driving connection may be in the nature of a gear connection 105 including a gear 41 on the projecting end of each shaft 23, meshing or cooperating with a gear 42 on the central or engine shaft 35^a. The gears 41 and the gear 42 are related to provide for the 110 proper synchronization of the rotors 12 and the rotor 13. In the particular case illustrated in the drawings, the gears 41 and the gear 42 are of the same effective diameters. A suitable gear case 43 is carried by the caps 28 and 40 to enclose the 115 gears 41 and 42. As clearly illustrated in Fig. 2 of the drawings, the driving rotors 12 are related so that their vanes 30 are in the same or corresponding rotative positions, and as the gears 41 120 cooperate with the common or central gear 42, the driving rotors 12 are maintained in this particular relation.

Passages or ports are provided in the block 10 to carry the actuating steam or fluid pressure to the chambers 11, and to carry the steam or fluid 125 exhausted from the chambers. In accordance with the invention, two parts communicate with each chamber 11 at circumferentially spaced points. Ports 44 are provided in the block 10 to communicate with the chambers 11 at points 130 spaced at opposite sides of the juncture of the bore 18 with the chambers. The ports 44 extend through the block 10 to its upper and lower ends, the upper ends of the ports 44 of the respective 135 chambers 11 being relatively close together as clearly illustrated in Fig. 2 of the drawings. The ports 44 communicate with the chambers 11 at points spaced substantially 90° apart. Exhaust ports 45 extend horizontally or transversely into the block 10 adjacent its upper and lower ends 140 and are spaced between the ports 44. The flow through the ports 44 and 45 is governed or controlled by the reversing valves 14 and the control valves 15, and as the reversing valves 14 are spaced between the control valves 15 and the ports in 145 150

the block 10, and must be set or adjusted before the motor can be operated, we will first describe the reversing valves and their operation.

The reversing valves 14 and the control valves 15 are carried by valve chests 46 arranged on the upper and lower sides of the rotor block 10. A reversing valve 14 is provided in each valve chest 46, and each valve 14 includes a body or plug 47 rotatable in a transverse opening 48 in a valve chest. The plugs 47 and the openings 48 are longitudinally tapered, and the opposite ends of the plugs project from the opposite sides of the valve chests. Two ports 49 are provided in each valve chest 46 and extend from the outer ends of the ports 44 to the opening 48. The ports 49 communicate with the opening 48 at substantially diametrically opposite points. Each valve chest 46 has an exhaust port 50 extending from the opening 48 to a port 45. The exhaust ports 50 join the openings 48 at points spaced between the ports 49. A pressure port or inlet port 51 is provided in each valve chest 46 and extends between a control valve 15 and the opening 48 of a reversing valve. The inlet ports 51 are diametrically opposite the exhaust ports 50. Two curved passages 52 are provided in each plug 48. The opposite ends of the passages 52 extend to the periphery of the plugs 48 and are spaced substantially 90° apart. It will be apparent how each reversing plug 48 may be positioned to have one of its passages 52 connecting a port 49 with an inlet port 51 and has its other passage 52 connecting a port 49 with an exhaust port 50. The plugs 48 are adapted to be turned to connect either one of the ports 49 with either the inlet port 51 or the outlet port 50, and in this manner, the admission of actuating fluid or steam to the chambers 11 and the discharge from the chambers may be governed to provide for the driving of the rotors 11 in either direction.

In accordance with the invention, an operative inter-connection is provided between the two reversing valves 14 whereby they may be simultaneously operated to reverse the flow through the motor and thus reverse the direction of rotation of the rotors 12. The large projecting ends of the reversing plugs 47 carry sprockets 53. A chain 54 passes over the sprockets 53 to operatively connect the plugs 47 of the two reversing valves. A suitable operating lever 55 is provided on the projecting end of the upper reversing plug 47. The plugs 47 of the two reversing valves 14 are related and positioned so that one port 44 of each chamber 11 is in communication with an inlet port 51 and the other port 44 of the chamber is in communication with an outlet port 50. Further, the reversing valves 14 are related so that one of the upper ports 44 is in communication with an exhaust port 45 and the other upper port 44 is in communication with an exhaust port 45, while one of the lower ports 44 is in communication with an exhaust port and the other lower port 44 is in communication with the lower inlet port 51. In this manner, each chamber 11 has one of its ports 44 operating as an inlet port and its other port 44 operating as an exhaust port. In the particular positioning of the valve illustrated throughout the drawings, the reversing plugs 47 are positioned so that the driving rotors 12 are rotated in the direction indicated by the arrows in Fig. 2, which of course, causes the master rotor 13 to be driven or rotated in the opposite direction.

The control valves 15 are provided to govern the admission of the actuating steam or fluid

pressure to the chambers 11. In the particular form of the invention illustrated in the drawings, the control valves 15 are in the nature of piston valves carried by the valve chests 46. Each control valve 15 includes a piston or valve proper 55 adapted to reciprocate in a cylinder 56. The ports 51 communicate with the cylinders 56 at points spaced between the ends of the cylinders. Steam or fluid pressure supply lines or ports 57 discharge into the cylinders 56 at points spaced between the ends of the cylinders. Steam or fluid pressure supply lines or ports 57 discharge into the cylinders 56 at points midway between their ends. The pistons or valves 55 are provided with annular grooves or ports 58 adapted to simultaneously register with the ends of the ports 51 and 57 to admit the actuating steam or fluid pressure to the chambers 11. In the particular relation of parts illustrated, the valve ports 58 are comparatively wide to remain in communication with the ports 51 and 57 during a large portion of each movement of each piston 55. It is obvious that the pistons or valves 55 close communication between the ports 51 and 57 during certain phases of operation of the motor. The control valves 15 are related so that their pistons or valves 55 are horizontal and therefore in parallelism, and so that their stems 59 project from the cylinders 56 in opposite directions.

The valve gear 16 is provided to operate the control valves 15 to provide for the admission of steam or fluid pressure into the chambers 11 during the driving or power portion of each revolution of each rotor 12. The valve gear 16 may reverse or reciprocate the valve pistons 55 so that the port 51 of each valve chest is in communication with a port 57 during approximately 270° of each rotation of a driving rotor 12 or during the movement of the vane 30 of said rotor from the inlet port 44 of its chamber 11 to the outlet port 44, it being understood that the valves 15 and the valve gear 16 may be set and related to operate in any desired or specific manner. The control valves 15 are synchronized by the valve gear 16 to provide for the proper relation between the admission and exhaust of the two chambers 11. The valve gear 16 includes like eccentrics 60 on the projecting ends of the driving rotor shafts 23. Eccentric straps 61 are operated by the eccentrics 60. The eccentric straps 61 have downwardly projecting rods or arms 62. Segmental or longitudinally curved reversing links 63 are pivotally mounted below the eccentrics 60 and at points spaced outwardly from the eccentrics. The reversing links 63 have their pivotal mountings 64 at their lower sides and spaced midway between their opposite ends. In the particular arrangement illustrated in the drawings, the reversing links 63 are arranged with their open or concaved sides facing upwardly. Each reversing link 63 is provided with a curved longitudinal slot 65. Pivotal connections 66 are provided between the lower ends of the eccentric arms 62 and the inner ends of the reversing links 63.

Radius rods 67 are pivotally and shiftably connected with the reversing links 63. The radius rods 67 extend upwardly from the reversing links 63 and their lower ends are pivotally connected with blocks 68 slidably longitudinally in the curved slots 65 of the links. The radius rods 67 are reciprocated or given longitudinal movement due to the rocking of the reversing links 63 and the strokes of the radius rods depend upon their points of connection with the links. One

of the radius rods 67 is operatively connected to the stem 59 of the upper control valve 15 by a rocker or bell crank having one arm 69 pivotally connected with the upper end of the radius rod 5 and having its other arm 70 pivotally connected with a link 71 attached to the outer end of the valve stem. The other radius rod 67 is operatively connected with the stem 69 of the lower control valve 15. Its upper end is pivotally connected with one arm 72 of a rocker or bell crank which has its other arm 73 extending downwardly and outwardly for connection with a transfer link 74. The transfer link 74 extends downwardly and is connected at its lower end to a bell 10 crank or rocker 75. A lever or link 76 is provided on the outer end of the stem 59 of the lower control valve and is pivotally connected with the rocker 75. A suitable case or housing 77 is provided on the block 10 to enclose the valve 15. The valve gear just described is operable to reverse or operate the two control valves 15 to provide for the proper admission and exhaust of steam or fluid from the chambers 11. The various parts of the valve gear 16 are proportioned 20 and related to provide for the desired synchronism of movement of the pistons 55 of the control valves 15.

The valve gear 16 is such that the blocks 68 at the lower ends of the radius rods may be shifted or adjusted along the links 63 to vary the strokes of the radius rods and control valves 15 and to shift the blocks 68 over the centers of the pivotal axes of the links 63 in order to reverse the relative action of the control valves 15 when the motor 30 is to be reversed. A reversing and controlling lever 80 is pivoted at its lower end to the inner side of the case 77 and projects upwardly through the upper end of the case 77 to have its upper end adjacent the upper end of the lever 55. Reach 35 rods 81 connect the lever 80 with the radius rods 67. The reach rods 81 are pivotally connected at 40 80^a with the lever 80 at points within the case 77 and in the particular structure illustrated, are normally substantially horizontal, their positions 45 of course, depending upon the setting of the radius rods. It will be apparent how shifting of the lever 80 results in adjustment or shifting of the radius rods 67 so that their points of connection with the links 63 are moved along the 50 links.

Means is provided for releasably holding or setting the lever 80 in any one of a plurality of different positions. A toothed quadrant 82 is provided on the upper end of the case 77. A 55 shiftable or releasable latch 83 is carried by the lever 80 to cooperate with the teeth of the quadrant. A pivoted handle 84 is provided on the lever 80 to operate or release the latch 83. After the release of the latch 83 the lever 80 may be shifted 60 to vary the strokes of the control valve pistons 55 and thus vary the speed of operation of the motor and may be shifted to move the points of connection of the radius rods with the links 63 between the opposite sides of the pivotal axes of 65 the links when the motor is to be reversed.

In operation assuming that the reversing valves 14 are set or adjusted to the positions illustrated in Fig. 2 of the drawings, the driving rotors 12 are rotated in the clock-wise direction as indicated by the arrows. The chamber 11 at the right-hand side of Fig. 2 has its upper port 44 in communication with an inlet 51 and has its lower port 44 in continuous communication with the lower exhaust port 45. The lower port 44 of 75 the chamber 11 at the left hand side of Fig. 2 is

in communication with the inlet port 51 of the lower valve chest, while the upper port 44 of this chamber is in constant communication with the upper exhaust port 45. The vane 30 of the right hand rotor 12 illustrated in Fig. 2 of the drawings has just left the groove 34 of the master rotor 13 and is passing over the upper port 44. During this phase of the cycle, the upper control valve 15 closes the port 51. Upon the vane 30 passing the port 44 the control valve 15 may move to the position where its port 58 is in communication with the port 57 and the port 51 so that the actuating steam or fluid pressure is admitted to the chamber 11 behind the vane 30. This steam or fluid pressure admitted to the chamber 11 acts upon the rear face or side of the vane 30 to drive or rotate the rotor 12. It is to be understood that the lower port 44 of the right hand chamber 11 remains open so that there is no resistance to movement of the vane 30 due to back pressure in the chamber. As the ports 44 are spaced approximately 90° apart and are positioned adjacent the lines of joinder of the bore 18 with the chamber 11, the actuating steam or fluid pressure may be admitted into the chamber 11 during substantially 270° of the cycle or movement of the vane 30, or in other words, until the vane 30 reaches or approaches the lower or exhaust port 44. Where an expansible actuating fluid such as steam is employed, the control 90 valves 15 may be set to provide for the proper expansion of the steam in the chamber 11 so as to obtain a maximum advantage of the available energy of the actuating pressure. When the vane 30 of the right-hand rotor 12 reaches the lower 95 port 44 or exhaust port 44, the control valve 15 may close, or may have been closed for a suitable portion of the cycle of the rotor, and thereafter remains closed until the vane 30 again passes the upper port 44. After the vane passes the lower 100 port 44 it enters or is received by the groove 34 of the master rotor and upon leaving the groove, again passes the upper port 44 whereupon the above described cycle of operation of the rotor is repeated. The cycle of operation of the left 105 hand rotor is repeated. The cycle of operation of the left hand rotor 12 is the same as that just described, with the exception that the actuating steam or fluid pressure is admitted into the chamber 11 through the lower port 44 and is exhausted 110 through the upper port 44 which remains open. As the vanes 30 of the two driving rotors 12 are in the same rotative positions, and as the rotors 12 rotate in the same direction at opposite sides of the master rotor 13, the vanes 30 alternately 115 or successively cooperate with the groove 34 of the master rotor at different portions of the cycle of the motor. This relation between the vanes 30 provides for the developing or delivering of 120 continuous power as one driving rotor 12 is passing through the active or power portion of its cycle during the time the vane 30 of the other rotor is passing from the exhaust port to the inlet port.

The master rotor 13, in having its periphery in 125 rolling contact with the peripheries of the two rollers 12 operates to separate the high pressure and the exhaust or low pressure portions of both of the chambers. The rotary motion or rotary power developed by the actuating steam or fluid 130 pressure acting upon the vanes 30 is directly transmitted to the shaft 35 through the timing and driving gears 41 and 42. It will be obvious that the gears 41 and 42 operate to maintain the proper timing or synchronism of the rotors 12 135 140 145 150

and the rotor 13. The stroke or movement of the control valves 15 may be readily governed by means of the lever 80. In order to reverse the motor, the lever 55 is shifted to turn the plugs 48 of the reversing valves 90° to change or reverse the relationship between the pairs of ports at the upper and lower sides of the motor. The lever 80 is then operated to shift connections of the radius rods 67 with the reversing links 65 10 over or past the pivotal centers of the reversing links so that the movement of the pistons of the control valves 15 is properly related to the reverse direction of rotation of the rotors 12. It is to be noted that the engine or fluid driven motor 15 of the present invention is particularly efficient as the vanes 30 of the two driving rotors 12 may be each acted upon or driven by the actuating steam or fluid pressure during approximately seventy-five per cent (75%) of their cycles so 20 that the greater portion of the available energy of the steam or fluid pressure is utilized. The motor operates smoothly and with little or no vibration, as it does not involve any large reciprocating parts. It will be understood how the 25 motor is adapted to be driven or operated by various classes of fluid under pressure, and how the motor is capable of being effectively employed in various situations and installations.

Having described only a typical form and application of our invention, we do not wish to be limited or restricted to the specific form or application herein set forth, but wish to reserve to ourselves any modifications or variations that may appear to those skilled in the art or fall within the scope of the following claims:

Having described our invention, we claim:

1. In a fluid motor, a body having two spaced openings and a third opening joining said spaced openings, rotors in said spaced openings, a vane 40 on each rotor adapted to be acted upon by fluid pressure admitted to the opening, a cylindrical member rotatable in the third opening, the periphery of said member having rolling contact with the peripheries of the rotors and having a groove 45 for receiving said vanes, the body having two ports communicating with one of said openings, and two ports communicating with the other opening, valve chests at opposite sides of the body each having a fluid pressure supply and an 50 exhaust, one of said ports from each of said openings being continuously open to one of the exhausts, valves in the chests governing the admission of fluid to the other of said ports, mechanical means actuating the valves, and a positive operative connection between the rotors and the said member.

2. A motor including, a body having two spaced 60 openings and a bore having a longitudinal axis parallel with the axes of said openings, the bore joining said openings, rotors in said openings, a vane on each rotor adapted to be acted upon by fluid pressure, a member rotatable in said bore and having its periphery in contact with the peripheries of the rotors, there being a groove in 65 the member for receiving the vanes, the body having two ports communicating with each of said openings, spaced exhaust ports, and spaced inlet ports, reversing valves for putting each of 70 the first mentioned parts in communication with the exhaust ports and inlet ports, control valves for the inlet ports, a valve gear for operating the control valves, and a driving connection between the rotors and said member.

3. A motor including, a body having two spaced

openings and a bore having a longitudinal axis parallel with the axes of said openings, the bore joining said openings, rotors in said openings, a vane on each rotor adapted to be acted upon by fluid pressure, a member rotatable in said bore and having its periphery in contact with the peripheries of the rotors, there being a groove in the member for receiving the vanes, the body having two ports communicating with each of said openings, spaced exhaust ports, and spaced inlet ports, reversing valves for putting each of the first mentioned ports in communication with the exhaust ports and inlet ports, control valves for the inlet ports, a variable and reversible valve gear for operating the control valves, and a driving connection between the rotors and said member.

4. A motor including, a body having two spaced openings and a bore having a longitudinal axis parallel with the axes of said openings, the bore joining said openings, rotors in said openings, a vane on each rotor having sliding engagement with a wall of an opening, a member rotatable in said bore and engaging the peripheries of the rotors, there being a groove in the member for receiving the vanes, the body having two ports communicating with each of said openings, one of the ports communicating with each opening being open to exhaust, control valves for governing the admission of fluid pressure to the other ports, and a driving connection between the rotors and said member.

5. In a motor of the character described, a body having two spaced parallel openings and a central opening parallel with said openings and joining said openings, rotors in the first mentioned openings, a vane on each rotor, a cylindrical member rotatable in the central opening and having its periphery in engagement with the peripheries of the rotors, there being a groove in the member for receiving the vanes, there being spaced ports in the body communicating with each of the first mentioned openings adjacent their points of joinder with the central opening, one port from each of said openings being continuously open to the exterior of the body to exhaust, mechanically actuated control valves governing the admission of fluid pressure to the other ports, and a driving connection between the rotors and said member.

6. A motor of the character described including, a body having a central bore, an opening parallel with and joining the central bore, and a second opening parallel with and joining the central bore, rotors in the first and second openings, a vane on each rotor, a member rotatable in the central bore and engaging the rotors, the member having a groove for receiving the vanes, spaced valve chests, each having an inlet and an exhaust, the body having two ports communicating with the first opening, one port extending to one chest, the other to the other chest, and having two ports communicating with the second opening, one port extending to one chest, the other port extending to the other chest, a reversing valve in each chest operable between a position where it connects one of the ports communicating with the chest with an inlet and connects the other port communicating with the chest with an exhaust and a position where the relation of the ports with the inlet and exhaust are reversed, control valves governing the inlets, reversing gear operating the control valves, and a drive between the rotors and said member.

7. A motor of the character described includ-

ing, a body having a central bore, an opening parallel with and joining the central bore, and a second opening parallel with and joining the central bore, rotors in the first and second openings, a vane on each rotor, a member rotatable in the central bore and engaging the rotors, the member having a groove for receiving the vanes, spaced valve chests, each having an inlet and an exhaust, the body having two ports communicating with the first opening, one port extending to one chest the other to the other chest, and having two ports communicating with the second opening, one port extending to one chest the other port extending to the other chest, a reversing valve in each chest operable between a position where it connects one of the ports communicating with the chest with an inlet and connects the other port communicating with the chest with an exhaust and a position where the relation of the ports with the inlet and exhaust are reversed, an inter-connection between the reversing valves whereby they may be simultaneously reversed, control valves governing the inlets, reversing gear operating the control valves, and a drive between the rotors and said member.

8. A motor of the character described including,

a body having a central bore, an opening parallel with and joining the central bore, and a second opening parallel with and joining the central bore, rotors in the first and second openings, a vane on each rotor, a member rotatable in the central bore and engaging the rotors, the member having a groove for receiving the vanes, spaced valve chests, each having an inlet and an exhaust, the body having two ports communicating with the first opening, one port extending to one chest the other to the other chest, and having two ports communicating with the second opening, one port extending to one chest the other port extending to the other chest, a reversing valve in each chest operable between a position where it connects one of the ports communicating with the chest with an inlet and connects the other port communicating with the chest with an exhaust and a position where the relation of the ports with the inlet and exhaust are reversed, control valves governing the inlets, reversible valve gear operating the valves, and a timing connection between the rotors and said member.
